UNITED STATES PATENT OFFICE.

JAMES H. TAYLOR, OF OWENSBORO, KENTUCKY.

DENTAL SURGICAL INSTRUMENT.

1,386,288.

Specification of Letters Patent.

Patented Aug. 2, 1921.

Application filed October 25, 1920. Serial No. 419,203.

To all whom it may concern:

Be it known that I, JAMES H. TAYLOR, a citizen of the United States, residing at Owensboro, in the county of Daviess and 5 State of Kentucky, have invented certain new and useful Improvements in Dental Surgical Instruments, of which the following is a specification.

This invention relates to dental surgical instruments and more particularly to an instrument designed for use in the operation of cutting away the bony process in which a malederupted molar has become impacted.

When a lower wisdom tooth is malederupted 10 or impacted, it will usually be found that the bony process of the inferior maxillary has grown over the upper side of the substantially horizontally projecting tooth. Therefore, one of the first requirements is to remove 15 this portion of the bony process so as to permit of the tooth being lifted from its impression, it being impracticable to extract the tooth on a direct line as its crown is presented directly toward the adjacent side of 20 the respective second molar. This disposition of the wisdom tooth when malederupted in the manner stated is due to the sharp upward curvature of the upper portion of the inferior maxillary.

In view of the foregoing the primary object 25 of the invention is to provide an instrument which may be conveniently manipulated without liability of injury to the patient and which will operate to smoothly 30 cleave or cut away the portion of the bony process of the inferior maxillary which has grown over the upper side of the malederupted molar. Thus by the use of the instrument 35 this portion of the bony process may by a single operation be cut away and removed 40 leaving a smooth surface which will quickly heal.

Another object of the invention is to so 45 construct the instrument that the same may be securely clamped or anchored to the molar and which will, when operated to cut away the bony process as above explained, exert a lifting action upon the molar tending to draw the same from its impression, so that, 50 other conditions being fairly normal, the actual extraction of the tooth after disengagement of the instrument therefrom, may be effected by the use of the ordinary forceps.

55 In the accompanying drawings:

Figure 1 is a side elevation of one of the

instruments embodying the present invention, the view illustrating the manner in which the instrument is to be employed in operating upon the malederupted or impacted 60 third molar at the left hand of the inferior maxillary;

Fig. 2 is a top plan view of the instrument;

Fig. 3 is a front elevation of the instrument, the same being illustrated clamped to 65 the molar;

Fig. 4 is a top plan view illustrating a modification of the instrument to adapt it for operation upon the right hand lower 70 third molar;

Fig. 5 is a detail longitudinal sectional view through the blade of the instrument;

Fig. 6 is a perspective view of the forward portion of one of the pivoted members of 75 the instrument.

The instrument shown in Figs. 2 and 4 of the drawings are of counterpart structure, and the only difference is that the one shown in Fig. 2 is adapted to be employed 80 in operating in the extraction of the lower left third molar, the instrument shown in Fig. 4 being designed for use in the operation of extracting the lower right hand third molar, and therefore reference numerals 85 which are employed in specifically describing the instrument shown in Figs. 1 and 2 will be applied to corresponding parts in Fig. 4.

Fig. 1 of the drawings illustrates clearly 90 the conditions under which the instrument shown in Figs. 1 and 2 is to be employed. In this figure, the reference letter A indicates the left side of the inferior maxillary bone and B the sharply upwardly curved 95 rear portion thereof. The second molar is indicated by the letter C and the third molar or wisdom tooth by the reference letter D. It will be observed that the third molar is malederupted or impacted so that it occupies 100 nearly a horizontal position, being embedded to a considerable extent in the bony process of the inferior maxillary. When this molar D is malederupted as illustrated in Fig. 1, its crown will be presented toward and in close 105 proximity to, if not in actual contact with, the rear side of the second molar C. It is evident that under the conditions illustrated it would be impossible to extract a malederupted molar by a direct withdrawal due 110 to the obstruction offered by the second molar C, and that before the molar B can

be lifted from its impression, the bony process of the maxillary A must be removed where it embeds the upper side of the molar, and it is for the purpose of removing this portion of the bony process that the instrument which will now be specifically described, is employed.

The instrument embodying the invention comprises a pair of crossed pivoted members 10 one indicated in general by the numeral 1 and the other by the numeral 2. The member 1 comprises a handle 3 which is provided near its forward end with a flattened portion 4 which is rotatably disposed 15 against a similar portion 5 formed at the forward portion of the handle 6 of the member 2. A pivot screw 7 has a threaded portion 8 which is tightly screwed into a threaded opening 9 formed in the portion 20 4 of the member 1, and a cylindrical shoulder portion 10 and a head 11 which latter portions are rotatably received within a similarly formed recess 12 in the portion 5 of the member 2. In this manner the members 1 and 2 are pivotally connected, and in order that their pivotal movement in a direction to bring the handles 3 and 6 toward each other, may be limited, the side members 1 and 2 are provided rearwardly of 25 their portions 4 and 5 respectively with co-acting shoulders 13 and 14. The handles 3 and 6 may be knurled or otherwise finished and may be of any shape best adapted to provide for convenient manipulation of 30 35 the instrument.

In order that the instrument may be clamped or anchored to the third molar preparatory to cutting away the portion of the bony process which embeds the upper side 40 of the molar, the member 2 is provided forwardly of its pivot with a forward extension 15 and a jaw 16 united by a flattened pivot portion 17. A jaw 18 is provided with spaced pivot ears 19 disposed to straddle the 45 pivoted portion 17 and a pivot pin 20 is fitted through the said ears and through the said pivot portion so that the jaw is pivotally connected for swinging movement with the jaw 16. The numeral 21 indicates 50 an interiorly threaded boss which is formed upon the inner side of the fixed jaw 16, and threaded into this boss is an adjusting screw 22 which extends through a slot 23 formed in the jaw 18 and is provided with a head 55 24 by which it may be rotated, the head bearing against the outer side of the said jaw 18 and being provided in its periphery with diametric openings 25 in which may be inserted the end of any suitable implement 60 which may then be employed as a lever for the purpose of rotating the screw to bring the jaws together in clamping the same to the molar. The jaws, in the present form of instrument, are turned downwardly 65 and forwardly from their pivoted ends, and

the opposing faces of the jaws at their outer or lower ends are cupped or concaved as indicated by the numeral 26, so as to enable them to embrace the opposite sides of the molar as clearly shown in Fig. 3 of the drawings. Referring to the said figure it will be evident that after the instrument has been disposed in the proper position, the adjusting screw 22 may be tightened so as to cause the jaw faces 26 to bind firmly 75 against the opposite sides of the molar to be extracted and thus the member 1 of the instrument is firmly clamped or anchored to the said molar.

The member 2 of the instrument is provided forwardly beyond its pivot with an extension 27 which is suitably arched to adapt it to clear the upper sides of the jaws 16 and 18, and the terminal portion of this extension is formed to provide a blade indicated by the numeral 28. This blade has a knife edge 29 which is suitably sharpened, and the outer side of the blade is suitably rounded both transversely and longitudinally, as indicated by the numeral 30, so as to provide a smooth surface, the opposite or inwardly presented face of the blade being concaved longitudinally and transversely, as at 31, so that the cutting edge 29 will be relatively thin and so that the blade 95 may more readily enter and cleave the bony process. If the instrument is disposed in substantially a horizontal plane as shown in Fig. 1 of the drawings, the cutting edge of the blade is presented downwardly and 100 forwardly as well as to a certain extent laterally at either side and it will be evident that after a suitable incision has been made in the gum and the jaws 16 and 18 have been securely anchored to the molar at a point close to the bony process in which the molar is embedded, an upward pull upon the handle 6 will cause the blade 28 to move downwardly and cut cleanly through the bony process. It will be evident that when 105 leverage is exerted against the handle 6 in the manner above stated, not only will the blade be moved downwardly to cut through the bony process, but the resistance offered to the blade will result in a tendency for the member 1 of the instrument to lift the jaws 16 and 18 so that as the process is cut away the instrument will be caused to exert a certain amount of force tending to elevate the molar from its impression, and thus the 110 operation of extraction is somewhat facilitated.

Having thus described the invention, what is claimed as new is:

1. A dental surgical instrument comprising a pair of pivoted handle members, tooth clamping means carried by one of said members, and a cutting blade carried by the other member.

2. A dental surgical instrument comprising

ing a pair of pivoted handle members, transversely alined tooth clamping means carried by one of said members, and a cutting blade carried by the other member and operating 5 in advance of the clamping means and having a concave side presented inwardly toward the said clamping means.

3. A dental surgical instrument comprising a pair of pivoted handle members, 10 pivoted jaws carried by one of said handle members, means for adjusting the jaws to clamp a tooth, and a cutting blade carried by the other handle member and movable therewith with relation to the clamping jaws 15 upon the first mentioned handle member.

4. A dental surgical instrument comprising a pair of pivoted handle members, one of said members being provided with an extension beyond its pivot, a jaw extending from the extension forwardly and thence in 20 a downward direction, a jaw pivoted to the first-mentioned jaw, the last-mentioned jaw having a slot, an adjusting screw having threaded connection with the first-mentioned jaw and extending through the slot, and a 25 cutting blade carried by the other handle member.

In testimony whereof I affix my signature.

JAMES H. TAYLOR. [L. s.]
